CLAIM

The ornamental design for a rocket lamp, as shown and described.

DESCRIPTION

FIG. 1 is a perspective view of the rocket lamp;

FIG. 2 is a top view thereof, on a reduced scale;

FIG. 3 is a left side view thereof, on a reduced scale;

FIG. 4 is a front view thereof, the back view thereof being a mirror image;

FIG. 5 is a right side view thereof, on a reduced scale; and,

FIG. 6 is a bottom view thereof, on a reduced scale.

The broken-line showing of environmental structure in FIGS. 1, 3, 4, and 5 is for illustrative purposes only and forms no part of the claimed design.
